CLAIM

The ornamental design for a hanger for a lavatory dispensing device, as shown and described.

DESCRIPTION

FIG. 1 is a perspective view of the top and front of my hanger;

FIG. 2 is a plan view of the rear of my hanger;

FIG. 3 is a plan view of a side of my hanger; the other side of my hanger which is not depicted in the figures is symmetrical with this side view;

FIG. 4 is a plan view of the bottom of my hanger;

FIG. 5 is a plan view of the front of my hanger;

FIG. 6 is a plan view of the top of my hanger;

FIG. 7 is a perspective view of the top and front of my hanger further illustrating in phantom a lavatory block;

FIG. 8 is a plan view of the front of my hanger further illustrating in phantom a lavatory block; and,

FIG. 9 is a plan view of a side of my hanger further illustrating in phantom a lavatory block.

The broken line showing of a lavatory block is included for the purpose of illustrating and forms no part of the claimed design.
